UNITED STATES PATENT OFFICE.

WILLIAM L. LARNED, OF NEW YORK, N. Y.

DESIGN FOR A FINGER-RING.

45,011.

Specification for Design.

Patented Dec. 9, 1913.

Application filed October 24, 1913. Serial No. 797,140. Term of patent 14 years.

To all whom it may concern:

Be it known that I, WILLIAM L. LARNED, a citizen of the United States, residing at New York, in the county of New York and State of New York, have invented a new, original, and ornamental Design for Finger-Rings, of which the following is a specification, reference being had to the accompanying drawing, forming part thereof.

The figure is a plan view of a finger ring showing my new design.

I claim:

The ornamental design for a finger ring, as shown.

WILLIAM L. LARNED.
